UNITED STATES PATENT OFFICE.

EDWARD H. SPERBERG, OF KANSAS CITY, MISSOURI.

MOVING-PICTURE MACHINE.

1,141,588.

Specification of Letters Patent.

Patented June 1, 1915.

Application filed December 23, 1913. Serial No. 808,379.

To all whom it may concern:

Be it known that I, EDWARD H. SPERBERG, a citizen of the United States, residing at Kansas City, in the county of Jackson and State of Missouri, have invented certain new and useful Improvements in Moving-Picture Machines, of which the following is a full, clear, and exact description, such as will enable others skilled in the art to which

10 it appertains to make and use the same.

The primary object of this invention is to promote the efficiency and insure the safety of moving picture machines, and more specifically to provide improved means for preventing projected light rays from reaching the film when the latter or its controlling mechanism is being adjusted.

In the accompanying drawings Figure 1 is a side elevation of a picture machine 20 equipped with my present improvements. Fig. 2 is a horizontal section on line 2—2, Fig. 1. Fig. 3 is an enlarged view of the film casing and its shutter showing the door closed. Fig. 4 is a view at right angles to 25 Fig. 3, the door being shown in its opened position in dotted lines.

The casing for the film operating mechanism (not shown) comprises opposite side walls 1 and 2 (Fig. 2), a front wall 3, and a rear wall 4, which latter is formed with the usual aperture to permit the light rays from the lamp to reach the film. The wall 1 has an upper extension for supporting the upper film magazine 5. This side wall 1 is attached to supporting base 7, and to it is also attached the lower magazine 9. To prevent ignition of the film, and serious consequences should ignition occur, both the upper and lower magazines are provided 40 with automatic closing means.

The opening to film-exposing portion of the casing is protected by a door 18 which, while allowing the proper light to pass to the film, will automatically prevent the projected light and heat from reaching the film when the door is partly or fully opened, thus enabling the attendant to gain access to the casing to adjust the film or its mechanism without danger of the light rays reaching the film. This door is shown (Fig. 2) in the form of a right-angle; it is hinged at 19 to the rear edge of side wall 1; its inner member is designed to fit against wall 4 and its outer member against the side wall 2, when the door is in its closed position. It has a swinging movement of 90°. Its

outer angular member carries a latch 20 for engaging a pin 21 under the influence of a spring 22 secured to the door at 23. The inner member of the door is provided with an opening 24 which coincides with an opening 25 in the rear wall 4. This door 18 carries an automatic shutter 27, which is pivoted at 26 and is under control of a spring 30 secured to the shutter at 31 and to the door at 32. Normally the aperture 33 of the shutter is out of alinement with apertures 24 and 25 in the door and casing, the movement of the shutter into aperture-closing position being limited by a stop 28 on the door in the path of a lug 29 of the shutter. (See Fig. 3.) When the door 18 is closed and the shutter is moved into the exposing position a lug 34 of the shutter engages a pin 35 projecting from the casing through an opening 36 in the door and holds the shutter in position with its aperture 33 coincident with apertures 24 and 25. When latch 20 is released the slightest opening movement of the door will disengage lug 34 from pin 35, and the shutter will instantly move to its closing position, under the recoil of its spring, thereby shutting off the light projected through apertures 24 and 25.

After the door is swung fully open, and while moving into that position, the outer member of the door will practically close the end of the projecting apparatus (see Fig. 2) and by intersecting the path of the light rays will prevent projected light from reaching the film through apertures 24 and 25, and hence the film or its mechanism may be adjusted in safety. When the door 18 is again closed the shutter 27 must be moved manually into aperture-exposing position before the light can project through the apertures.

The advantages of my invention will be readily appreciated by those skilled in the art. It will be observed that by means thereof, the danger of a film being ignited and of the serious consequences arising from ignition are greatly if not wholly eliminated.

Having described my invention, what I claim as new and desire to secure by Letters Patent, is:—

1. In a moving picture machine having a projecting apparatus, a casing, a door therefor composed of two members at right angles to each other, one of said members being hinged to the casing and provided with a light aperture, means for holding

said door closed, and means for automatically closing said aperture immediately upon the movement of the door on the release of the door holding means, the outer member of the door being designed to extend across the projecting apparatus when the door is opened.

2. In a moving picture machine having a projecting apparatus, a casing, a door therefor composed of two members at right angles to each other, one of said members being hinged to the casing and provided with a light aperture, a shutter carried by said member, means for holding such shutter in position to uncover said aperture when the door is closed, and means for automatically moving such shutter to cover such aperture immediately upon the opening of the door, the outer member of the latter being designed to extend across the projecting apparatus when the door is opened.

3. In a moving picture machine having a projecting apparatus, a casing, a door therefor composed of two members at right angles to each other, one of said members being hinged to the casing and provided with a light aperture, a shutter carried by said member and having an aperture designed to

register with the aperture of the door, means for holding such shutter with its aperture 30 in register with that of the door while the door is closed, and means for automatically moving the shutter to conceal the aperture of the door immediately upon the door being moved after being released by the door holding means, the outer member of the door being designed to extend across the projecting apparatus when the door is opened.

4. The combination with a casing and a stud projecting therefrom, of a door for the casing having a light aperture therein, a shutter carried by the door for closing said aperture, said shutter being pivoted to the door and having a lug designed to be engaged and held by said stud when the door 45 is closed, a spring for moving said shutter to cover said aperture when the door is opened, and a stop for limiting the movement of the shutter.

In testimony whereof I affix my signature 50 in the presence of two witnesses.

EDWARD H. SPERBERG.
